UNITED STATES PATENT OFFICE.

HARRY VISSERING, OF KENILWORTH, ILLINOIS.

CONTROLLING MECHANISM FOR LOCOMOTIVE WHISTLES.

Application filed October 8, 1925. Serial No. 61,368.

The invention relates to controlling mechanism for locomotive whistles.

In modern railway operation, it is necessary for the engineer to operate the signal whistle when approaching road crossings, and one object of the invention is to provide readily and conveniently operable controlling means for the whistle. Another object of the invention is to provide improved controlling mechanism which includes a pneumatically operated device, as well as a hand-operable device for controlling the whistle. Other objects of the invention will appear from the specification.

15 The invention consists in the several novel features hereinafter set forth and more particularly defined by claims at the conclusion hereof.

15 In the drawings: Fig. 1 is a diagrammatic view of a locomotive equipped with the invention. Fig. 2 is a section of the device for controlling the supply of air to the pneumatic whistle-controlling piston for operating the valve for the steam whistle. Fig. 3 is a section taken on line 3—3 of Fig. 2. Fig. 4 is a detail perspective of the air inlet valve in the device shown in Figs. 2 and 3. Fig. 4^a is a side elevation of the handle and stem for shifting the air inlet valve. 20 Fig. 5 is a section, illustrating the improved whistle-operating device. Fig. 6 is a section taken on line 6—6 of Fig. 5. Fig. 7 is a section taken on line 7—7 of Fig. 6. Fig. 8 is a detail perspective of one of the members of the jointed lever for shifting the steam valve for the whistle.

25 The invention is exemplified in connection with a whistle 12 which may be of usual or suitable construction, and is adapted to be operated by the discharge of steam into it, as well understood in the art. This whistle is secured by a bolt 13 and a retaining nut 14, on the top of the casing containing the valve which controls the delivery of steam to the whistle, and a piston adapted to be operated by fluid under pressure for operating the valve.

30 This casing comprises a nipple 15, which is adapted to be screw-threaded into the top of the boiler, so as to receive steam through its lower end. A valve 16 is normally seated on a seat 17 in the lower end of the nipple 15, and is integral with a stem 18, which is vertically slidable in a cylindrical guide 19 in said stem. The casing also comprises a body 20, integrally formed with and above the nipple

15. An annular chamber 21 is formed in said body. The stem 18 is formed with vertical ducts 22 for conducting the steam, admitted by valve 16, from the lower end of the nipple 15 to the chamber 21, the lower portion of which extends inwardly so that it will be in constant communication with the upper end of the stem 18. A suitable discharge opening 23 for the steam is formed in the casing to 20 discharge the steam into the whistle, so that it will produce a noise, as well understood in the art. A screw 24 is threaded into the nipple 15, and has a stud 25 at its inner end which extends into a cross-slot 26 formed in 25 the stem 18 to hold the stem against rotation.

30 The invention contemplates the provision of a device operable by fluid under pressure, usually air, for opening the steam-valve 16, and the inclusion of this device in the valve-casing. For this purpose, an annular wall 28 is integrally formed with the casing, being united to the bottom of the body 20 of the casing by lugs 29, and a cylinder 30 is formed in said wall. A piston 31 is fitted and vertically slidable in said cylinder. A stud 32, riveted to piston 31, extends through the bottom wall 33 of the cylinder, and is adapted to engage the upper end of the valve-stem 18, to open the valve 35 35 40 45 50 55 60 65 70 75 80 85 the air supply connection, two oppositely disposed ports 39 are formed in the casing, and the port not used is closed by plug 39^a. Ducts 40 are formed in the casing, and lead from the lower end of the cylinder 30 to the outside of the casing, so that the piston will be free to be operated downwardly by the air under pressure, and so that the piston will not become air-bound.

- 10 The construction described exemplifies one in which the pneumatically operated piston is mounted in the valve-casing and within the annular chamber through which steam passes to the whistle. As a result of this construction, all danger of the air-operated piston becoming frozen in cold weather is avoided, because the steam passing around the cylinder of the piston will prevent this; also one in which the piston is located for direct action 15 on the steam-valve, so that the structure will be compact and simple.

In practice, it is desirable to provide for the manual operation of steam valve 16, as well as the fluid-pressure operated device, for 20 use in event the latter should become inoperative. This manually operable device comprises a lever 42, which is pivotally connected by a pin 43 to ears 44, integrally formed with the valve-casing, and is provided with a round terminal 45 which extends into the cross-slot 19 in the valve-stem 18, so that when the lever is rocked to move said terminal downwardly, the valve-stem 18 will be shifted downwardly to open the valve and admit steam to the 25 chamber 21 for the operation of the whistle. Lever 42 comprises an arm 46, which is riveted at 47 to a member 48, which is pivoted, at 49, to the free end of lever 42. Member 48 is U-shaped in cross-section, and its cross or 30 connecting wall 50 is adapted to abut against one edge of the lever 42, so that when arm 46 is moved forwardly, it will, in effect, be rigid with the lever 42, and shift the latter to operate the valve 16. The side of member 48, opposite 35 the wall 50, is open, so that when lever 42 is shifted by the piston 31, the pivotal connection 49 between member 48 and lever 42 will permit the lever to swing relatively to arm 46. This constitutes, in effect, a one-way connection 40 between the arm 46 and the lever 42, which permits the lever 42 to move with the valve 16 when the latter is operated by the piston 31, without shifting the connections between arm 46 and the cab. The operating 45 connection between arm 46 and the cab consists of a rod 51, which has its front end pivoted at 52 to arm 46, and its rear end pivoted to a lever 53, which is fulcrumed at 54, a bell-crank lever 55, which is fulcrumed at 56, and 50 provided with an operating handle 57, and a link 58 between levers 55 and 53. When it is desired to manually operate the valve 16, the engineer will depress the handle 57 to rock lever 55, which will retract link 58 to swing lever 53 and push rod 51 forwardly to oper-

ate arm 46. When said arm is pushed forwardly, the wall 50 of member 48 will render the arm rigid with lever 42, and swing said lever so that its terminal 45 will force open the valve 16.

70 In the operation of locomotives at the present time, it has become necessary for the engineer to frequently operate the whistle in approaching road-crossings and stations. The construction set forth exemplifies one in which the steam valve for the whistle is operable by a fluid-operated piston, and in which the lever for the manual operation of the valve is so constructed that the operating lever and connections in the cab will not be displaced when the steam valve is operated by the piston. This is desirable, because the locomotive cab contains so many controlling devices, that it is desirable to avoid the displacement of any which is not in use.

75 A device for controlling the delivery of air under pressure to pipe 38, to control the operation of the piston 31 from the engineer's cab, comprises a casing 60 which is conveniently mounted on a bracket 61 inside of the locomotive cab. A pipe 62, which is connected to receive air from the main air reservoir on the locomotive is connected by a coupling 63 to a nipple 64 on the lower end of the casing 60 to deliver air to the casing. A valve 65 is 80 slidable in a chamber 66 in said casing, and is adapted to close against a seat 67. Said valve is formed with guide-ribs 68, and is held normally closed by a coil spring 69, which is confined in the coupling 63 and 85 bears against the under side of said valve. The body of the casing 60 is formed with a chamber 70, to which is connected the pipe 38 which delivers air under pressure to the casing for piston 31 and the steam-valve. A 90 shaft or stem 71 extends through and is journaled in one side of the casing, and has a projecting stud 72 to which is secured an operating handle 73, which is preferably split and clamped around the stud by a screw 74. 95 The inner end of stem 72 extends into a bearing 75 in a cap 76, which is threaded into the opposite side of the casing. To prevent leakage of air from the chamber 70 and 100 around the stem, the latter is formed with an annular shoulder 77, which bears against packing ring 78 held in the casing, and a coil-spring 79 is applied between the stem and the cap 76 to force the shoulder against the packing. Stem 71 is provided with a lug 80, 105 which is formed with a socket 81, and is adapted to operate a loose plunger 82 to open the valve 65. The lower end of stem 71 is 110 confined in a socket 83 in the upper end of valve 65, and a coil spring 84 is applied between lug 80 and the bottom wall of the casing 60 to retract stem 71 and hand-lever 73. In order to release the piston 31 and 115 permit the steam-valve 16 to close when the supply of compressed air is cut off at valve 120

65, the stem 71 is provided with a lug 85 for operating an exhaust valve 86. Said exhaust valve is slidably mounted in a lug 87 in the casing 60 and in a guideway 88 in one of the 5 side walls of the casing. One end of the valve 86 is adapted to close against a seat 89 formed in the casing, and which is in communication with an exhaust pipe 90. A coil spring 91 is applied between a plug 92, which is screw- 10 threaded into the casing and the valve 86, to close said valve when the handle 73 is operated to open the admission valve 65. Lug 85 extends into a notch 93 formed in the lower side of the valve 86, and the end of the notch 15 engaged by lug 85 is disposed so that valve 86 will be incidently closed during the initial movement of the lever 73 to open valve 65. The notch is elongated to permit the lug 85 to move independently of the valve 86 after 20 the latter has been closed. In the operation, the engineer, when the steam-valve 16 is to be pneumatically operated, will depress the free end of handle 73. During the initial movement, exhaust valve 86 will be closed by 25 spring 91, and lug 85 will recede from the inner end of notch 93. After valve 86 has been closed, lug 80 will depress the plunger 82 and open valve 65, so that compressed air from pipe 62 will flow through chamber 70 30 and pipe 38 into cylinder 30 to operate the piston 31. The latter will force open the steam valve 16 to operate the whistle. When the handle 73 is released, lug 80 will move upwardly to release plunger 82 and permit 35 the admission valve 65 to close before lug 85 engages the inner end of notch 93 in the exhaust valve 86. After the admission valve 65 has been fully closed, lug 85 will open valve 86, so that the air under pressure from cylinder 30 will be exhausted through pipe 28, 40 chamber 70 and the pipe 90. This air-control valve exemplifies one which is simple in construction, which will occupy little space in the engineer's cab, and which conjointly controls the admission of compressed air to the piston 31 and the exhaust of air at the end of 45 each operation of the whistle.

The invention is not to be understood as restricted to the details set forth, since these 50 may be modified within the scope of the appended claims, without departing from the spirit and scope of the invention.

Having thus described the invention, what I claim as new and desire to secure by Letters Patent, is:

1. In a signalling mechanism for a locomotive, the combination of a steam whistle, a casing adapted to be positioned outwardly of the locomotive cab and provided with 50 means for connection to a steam supply, said casing being associated with the whistle and adapted to supply steam thereto, a valve in the casing for controlling the supply of steam to operate the whistle, a fluid-pressure operable piston also mounted in the casing and

adapted to open the steam-valve, a lever for opening the steam-valve disposed adjacent the casing, said steam-valve being mounted so that it will not displace the piston when shifted by said lever, a valve mounted in the cab 70 and connected to control the delivery of fluid under pressure to the piston, and a connection between the lever and said cab whereby the steam-valve may be manually shifted 75 from the cab.

2. In a signalling mechanism for a locomotive, the combination of a steam whistle, a casing adapted to be positioned outwardly of the locomotive cab and provided with means at its lower end for connection to a steam supply, said casing being adapted to supply steam to the whistle, a valve for controlling the supply of steam to operate the whistle mounted in the casing, a fluid-pressure operable piston also mounted in the casing and adapted to open the steam-valve, the casing being provided with a chamber around the piston from which steam passes from the valve to the whistle, a lever pivoted to the casing and connected directly to the steam-valve to shift the latter, a valve mounted in the cab and connected directly to the steam-valve to shift the latter, a valve mounted in the cab and connected to control the delivery of fluid under pressure to the piston, and a connection between the lever and said locomotive cab whereby the lever may be manually shifted to open the steam-valve so as to operate the whistle.

3. The combination with a whistle for a locomotive, of a valve for controlling the supply of steam for operating the whistle, fluid-operated means for opening the valve, a lever for shifting the valve comprising relatively movable members, one of which is movable with the valve, and a manually operable connection between the other member and the locomotive cab, the connection between the members permitting the lever member connected to the valve to be operated by said fluid-operated means without displacing the connection to the cab.

4. The combination with a whistle for a locomotive, of a valve for controlling the supply of steam to the chamber for operating the whistle, a fluid-operated means for opening the valve, a lever for shifting the valve comprising pivotally connected members, one of which is pivoted to the valve, and a manually operable connection between the other member and the locomotive cab, the pivotal connection between the members permitting the lever member connected to the valve to be operated by said fluid-operated means without displacing the connection to the cab.

5. The combination with a whistle for a locomotive, of a casing provided with a chamber, a valve for controlling the supply of steam to the chamber for operating the whistle, a fluid-operable piston in the cas-

ing and adapted to open the valve, a lever for shifting the valve comprising pivotally connected members, one of which is movable with the valve, a manually operable connection between the other member and the locomotive cab, and a one-way operating connection between the members permitting the lever member connected to the valve to be operated by the piston without displacing the connection to the cab.

6. The combination with a steam whistle, a casing, a valve for controlling the delivery of steam to the casing for the operation of the whistle, and a fluid-pressure operated piston for operating the valve, of a device for controlling the operation of the piston from the cab comprising a casing having a chamber therein connected to a source of supply of compressed air, an admission valve vertically slidable in said latter casing, an exhaust valve horizontally slidable in said latter

casing, and a shaft journalled in the latter casing provided with lugs for successively operating the admission and exhaust valves.

7. The combination with a steam whistle, 25 a casing, a valve for controlling the delivery of steam to the casing for the operation of the whistle, and a fluid-pressure operated piston for operating the valve, of a device for controlling the operation of the piston from the cab comprising a casing having a chamber therein connected to a source of supply of compressed air, an admission valve vertically 30 slidable in said latter casing, an exhaust valve horizontally slidable in said latter casing, a shaft journalled in the latter casing provided with lugs for successively operating the admission and exhaust valves, and a handle fixed on said shaft.

Signed at Chicago, Illinois, this 6th day 40 of October, 1925.

HARRY VISSERING.
